UNITED STATES PATENT OFFICE.

WILLIAM McG. SMITH, OF LONDON, ENGLAND.

CENTRIFUGAL MACHINE.

SPECIFICATION forming part of Letters Patent No. 656,055, dated August 14, 1900.

Application filed October 22, 1898. Serial No. 694,317. (No model.)

To all whom it may concern:

Be it known that I, WILLIAM MCGREGOR SMITH, a subject of the Queen of Great Britain, residing at London, England, have invented certain new and useful improvements in apparatus for treating ramie, china-grass, and other vegetable fibers, also applicable for the drying of grain and other articles or materials, of which the following is a full, clear, and exact description, and for which I have made application for British Patent No. 7,690, dated March 30, 1898.

Ramie fiber after being degummed or after being bleached is at present usually put into a centrifugal machine in which a portion of the moisture contained in it is removed, and it is afterward placed in a drying-stove to be completely dried. Other vegetable fibers and grains are in like manner partially dried in centrifugal machines and afterward completely dried in drying-stoves or in the open air.

I will describe my invention in connection with the accompanying drawings, in which—
Figure 1 is an elevation, and Fig. 2 a plan, of one arrangement of apparatus such as I employ in carrying my invention into effect. Fig. 3 is an elevation, and Fig. 4 a plan, of similar apparatus to the above, but with a heater for superheating the steam or heating the air, &c. Fig. 5 is a vertical section of the centrifugal machine separately; and Fig. 6 is a side elevation, and Fig. 7 an end elevation, of the heater separately. Fig. 8 is a sectional detail view, on a larger scale, showing the separation of the true and false bottoms. Fig. 9 is a sectional detail view, on a larger scale, showing the cover bolts or studs.

In all the figures like parts are indicated by similar letters of reference.

With my improved apparatus the treatment of ramie and other vegetable fiber and grain results in effecting a larger proportion or the whole of the drying in a centrifugal machine by treating them while in the machine, with steam, the effect of such treatment being at once to soften and to brighten the fiber and to dry the grain.

For the sake of clearness I will speak in describing this invention of the treatment of ramie fiber only; but it will be understood

that similar treatment is applicable also to various kinds of vegetable fiber, grain, and spent grains and many other substances and articles.

55

Centrifugal machines, such as *a*, used for drying fiber are frequently driven from an engine *b*, having a vertical crank-shaft *c*, on which is fixed a pulley *d*, motion being conveyed from the engine *b* to the centrifugal machine *a* by means of a belt *e*, communicating the motion to the centrifugal machine by means of a pulley *a²*, fixed upon the spindle *a'* of the centrifugal itself.

The steam desired for the treatment of the fiber in the centrifugal machine may conveniently be obtained from the exhaust-steam of the driving-engine *b*. In order to effect this end, the exhaust-pipe *f* of the engine communicates with a steam-receiver *g*, arranged in any well-known manner, so as to detain any water, grease, and other dirt passing along with the steam and to prevent it from passing forward, and of such a capacity that the intermittent and the pulsatory action of the steam from the engine *b* may be converted into a continuous and almost equal flow. From this receiver *g* the steam passes by the pipe *g'* into a fixing or small chamber *a³* upon the casing of the centrifugal *a*, the centrifugal itself being provided with a cover *a⁴* to prevent the free admission of air at the upper part and prevent the free escape of the steam. The pipe *g'* is fitted with a valve *g²* to enable the steam to be cut off when not required. The cover *a⁴* is so arranged that it can easily be lifted for the putting in of the material and for its removal. A fixture *a⁵* is secured upon and movable with the cover *a⁴* and extends over the chamber *a³* and is so arranged that when the cover is closed a passage is provided through which the steam can pass to the center of the cover, where it enters a projecting pipe *a⁶*, descending into the perforated or foraminous basket *a⁷* of the centrifugal machine. The arrangement of the various parts is such that a fairly-close joint is made, so that little or no steam escapes, but the whole or almost the whole of the steam passes through the central pipe *a⁶* into the revolving basket *a⁷* of the machine.

90

In Fig. 5 I have shown the cover *a⁴* of the

95

100

centrifugal machine hinged at a^{11} to the body of the machine and adapted to be correctly fixed or adjusted in position on the casing a and the chamber a^3 by bolts or studs a^{12} , secured to and carried by the cover a^4 and its attached fixture a^5 , engaging corresponding recesses in the upper edge of the chamber a^3 . (See details, Fig. 9.) I have also shown the top of the centrifugal basket a^7 removable and capable of being fixed or secured in place on the basket a^7 by sliding bolts a^{13} , arranged in suitable guides on the top or cover, engaging openings in lugs a^{15} on the body of the basket a^7 .

15 a^{11} is a counterbalance carried by the cover a^4 .

a^{16} is a drip-pipe for the water of condensation, and a^{17} is a pipe leading to the exhaust, as usual.

20 The steam, as described, enters the basket a^7 of the machine in a downward direction, so that any moisture which it may contain is thrown downward, and within the machine I provide a loose dome a^8 , slightly conical in form, projecting upward to the level of the top of the basket a^7 or thereabout, open at its upper end and provided at its lower part with a plate a^9 , which forms a false bottom supported at the bottom of the basket a^7 , but

25 prevented from touching it by bars or rods a^{10} , (see details, Fig. 8,) which preserve a short distance between the false bottom a^9 and the true bottom of the revolving basket. Any water thrown downward by the steam or condensing upon the dome a^8 is accordingly guided below this false bottom a^9 and passes out through the side of the basket opposite the space between the true and false bottoms without passing through the fiber in the machine.

30 The steam, however, rising above and out of the dome a^8 can pass into the basket a^7 and come into contact with the fiber, so that the fiber while undergoing the operation in the centrifugal machine is in an atmosphere of steam. The effect of this is to render the fiber hot and to cause it more freely to part with moisture, while at the conclusion of the operation the heat remaining in the fiber is sufficient to evaporate a portion or the whole of the moisture which may

35 still remain combined with the fiber. At the same time the action of the steam upon the fiber softens it and renders it more pliant and brighter in appearance; but in the case of grains the apparatus is only used for drying the same.

In some cases, in order more thoroughly to dry the fiber contained in the centrifugal machine, I introduce a superheater h (see Figs. 3, 4, 6, and 7) between the steam-receiver already described and the point at which the steam enters the centrifugal machine. The superheater h may be somewhat similar in construction to an arrangement of surface condenser as used in some condensing-engines, the superheating being effected either

by passing the steam through tubes which on the outside are heated by steam at a higher pressure or by passing the steam around tubes which on the inside are heated by steam at a higher pressure. This superheated steam coming in contact with the fiber containing moisture will evaporate a portion of the moisture and so dry the fiber.

In some cases I may use an apparatus similar to the above for heating air, which may be made to follow the application of steam. The same apparatus may indeed be used first for superheating steam to be used in the centrifugal machine, and afterward, the superheating of the steam having been stopped and the passage of steam from the receiver into the centrifugal machine having also been stopped, (arrangements being made so that the steam can escape into the atmosphere,) for heating the air, and in some cases the air may be forced through this apparatus and into the machine by a fan or by other means for producing an artificial flow of air. This combined arrangement for supplying either superheated steam or hot air to the centrifugal machine is illustrated in Figs. 3, 4, 6, and 7. In this case the superheater h is connected with the steam-receiver g by a pipe h' , provided with a valve h^2 , and with a fan i by a pipe h^3 , provided with a valve h^4 , while the steam-receiver g is also connected directly with the fixing or small chamber a^3 by a pipe g' , as before described. The fan i is driven from the engine by means of pulley d' on engine-shaft, belt j , and pulley i' on fan-shaft.

When heated air is forced into a centrifugal machine for the purpose of completing the drying, I usually make the dome somewhat lower than the top of the centrifugal basket, and I make the top rim of the basket of such a width as to extend inward considerably beyond the position of the dome. It is necessary in this case to make the top rim of the basket removable, as otherwise it would be difficult to introduce fiber into the machine and remove it therefrom. It is also often convenient in other cases to make the top rim removable, as otherwise the space between it and the dome is not sufficient to enable the fiber to be easily introduced and removed.

If desired, steam may be conveyed direct from a steam-engine to the steam-receiver.

Having thus fully described my invention, what I claim, and desire to secure by Letters Patent, is—

1. In centrifugal apparatus, the combination of a casing, a small chamber attached to one side of said casing, a steam-pipe leading into said chamber, a hinged cover for the casing, a fixture on said cover forming a passage for the steam from the small chamber to the center of the cover, means for positioning said cover and fixture on the casing and chamber, and an exhaust-pipe attached to the casing, substantially as set forth.

2. In centrifugal apparatus, the combina-

tion of a casing, a hinged cover for said casing, means for positioning said cover on the casing, a downwardly-projecting pipe carried by said cover, a perforated basket arranged in the casing, a removable top for said basket, a loose dome in said basket, and a plate attached to said dome forming a false bottom for said basket, substantially as set forth.

3. In centrifugal apparatus, the combination of a casing, a small chamber attached to said casing, a steam-pipe leading into said chamber, a hinged cover for the casing, a counterbalance attached to said cover, a fixture on said cover forming a steam-passage 15 between said casing and chamber, means for positioning the cover and fixture on the casing and chamber, a downwardly-projecting pipe carried by said cover, a perforated basket arranged in said casing, a removable top 20 for said basket, means for locking the top to the basket, an opening in the said top, a loose dome in said basket, an opening in the top of the dome for said downwardly-projecting pipe, a plate attached to said dome forming a

false bottom to the basket, and a steam-exhaust pipe attached to the casing, substantially as set forth. 25

4. In centrifugal apparatus, the combination of a casing, a small chamber attached to said casing, a steam-pipe leading into said small chamber, a hinged cover for the casing, a fixture on said cover forming a steam-passage 30 between said casing and chamber, means for positioning said cover and fixture on the casing and chamber, a downwardly-projecting pipe carried by said cover, a perforated basket arranged in said casing, a loose dome in said basket, a plate attached to said dome forming a false bottom, bars for said plate to rest upon, and an exhaust-pipe for the steam, 35 attached to the casing, substantially as set forth. 40

In testimony whereof I affix my signature in presence of two witnesses.

W. MCG. SMITH.
